UNITED STATES PATENT OFFICE.

KARL LENCK, OF BERLIN, GERMANY.

COPYING-PRESS WITH PRESSING-LEVERS ARRANGED SYMMETRICALLY TO ONE ANOTHER.

No. 916,730.

Specification of Letters Patent.

Patented March 30, 1909.

Application filed March 30, 1908. Serial No. 424,106.

To all whom it may concern:

Be it known that I, KARL LENCK, a subject of the German Emperor, and resident of 154 Friedrichstrasse, Berlin, N. W. 7, Germany, have invented certain new and useful Improvements in Copying-Presses with Pressing-Levers Arranged Symmetrically to One Another, of which the following is a specification.

10 In the copying presses already known and having eccentric levers the eccentric pressure acts either directly on certain points in the pressing plates, or the eccentric levers press down springs which in turn transmit their 15 force of pressure to certain points in the pressing plates. Hereby however a good copy is only obtained in the places where the pressure is applied, while in consequence of insufficient pressure the remaining portions 20 of the copy are indistinct or are not visible at all. This disadvantage is obviated by the present invention, as when the eccentric levers are turned over the pressure is transmitted uniformly from the middle toward 25 both sides, the springs being continuously pressed against the pressing plate. The eccentric levers can moreover be suitably adjusted for books of different thickness. This however is not effected as heretofore by 30 screwing up the pressing lever bearings higher or lower by catches, but by placing the pressing levers in certain lugs adapted to the current thickness of the books.

In the accompanying drawing, in which I 35 have illustrated my invention like numerals of reference refer to like parts throughout the different views.

In said drawings, Figure 1 shows an elevation of my improved eccentric press. Fig. 2 40 shows a plan-view of Fig. 1. Figs. 3-9 show a modified form of construction of my improved eccentric press.

In Figs. 1 and 2 of the drawing the lower 45 pressing plate is indicated as 1, the upper pressing plate as 2. Between the two is the space for the copying book, which is compressed by forcing the pressing plates one toward the other. The tension rods 3 which 50 are bent to a U shape embrace the pressing plates so that the lower plate lies firmly therein, while the upper plate can be easily raised and lowered between the arms of the bent rods. The relative positions of the plates and rods is maintained in the simplest 55 manner by forcing grooves in the sides of the

pressing plates into which the arms of the rods engage. The free ends of the tension rods are bent to form eyes 4 which serve as bearings for the eccentric levers. On the upper pressing plate 2 are fixed pressure distributing springs 5 consisting of rods which are suitably bent at their ends to form elongated eyes or lugs. In order to move the pressing plates one against the other it is thus only necessary to lower the pressing 60 springs 5 in relation to the tension levers 3, this being effected in a simple manner by the eccentric levers 7. Each of these levers is bent to a U shape while the part joining the two arms of the U is bent upward to enable it 65 to be conveniently held by the hand. Each of the two free ends is bent three times at right angles so that two cranks which stand apart are produced. One crank engages the eye 6 and the other the eye 4. By turning 70 the lever over inward on to the pressing plate 2 the eye 6 is lowered to double the extent of the distance between the two bearing pins of the eccentric levers 7. By suitably bending these levers any desired pressure can be applied in the press. The bend is moreover so arranged that after touching the pressing plate the levers 7 remain stationary, that is in the position shown in the drawing in full lines, and so likewise after they have been 80 put back outward and downward. In the latter position the pressing springs 5 and the levers 7 are stationary in relation to one another so that they form a convenient support 85 for the copying book. The lever 7 must 90 therefore stand somewhat higher than is shown in the drawing (Fig. 1). This position is determined by the length of the eyes 6, within which the inner crank bearing of the eccentric lever slides to and fro. The 95 pressing springs 5 are suitably fixed in the middle on the upper pressing plate 2, in order that the pressure may be distributed uniformly over the copying surfaces.

In the modified form of construction 100 shown in Figs. 3 and 5 of the drawing band springs 8 are arranged instead of the springs 5, for the purpose of obtaining a more powerful pressure, particularly for thick copying books. The lugs 9 in the band springs can 105 be produced by simply bending the band springs. In order to enable the press to be used for a number of book thicknesses it is only necessary to seat the cranks of the levers 7 higher or lower. Such a variable seating 110

can be obtained by bending the free ends of the tension rods so as to form not one eye or lug but a number of eyes or lugs. By compressing the bent levers 7 the outer bearing pins are removed from the lugs 4. Hereupon the lever 7 may be raised somewhat higher up to the second lug 10 and is then released, so that the pins catch in these upper lugs. The pressing plate 2 with the springs 8 is thereby put out of the position indicated by dotted lines into that indicated by full lines (Fig. 3). If the difference in the thickness of the books is only slight, it is only necessary to turn the free wire ends of the tension levers 3 over the lugs in the manner shown in Figs. 5 and 6. If the lug is to be higher a new lug is formed by turning the wire around completely to the desired height.

The details of the press may vary considerably in construction. For example (see Figs. 7-9) the pressing plates 1 and 2 can be dispensed with by bending a pressing plate 11

laterally and forming it above with lugs 12 at the ends, so that the tension rods 3 are also unnecessary. The upper pressing plate may likewise be replaced by a plate 13 which at the same time renders the springs superfluous, as it is furnished with lugs 14.

What I claim as new and desire to secure by a United States Letters Patent is:—

In a copying press the combination of two press plates, rods connected to the lower press plate and having eyelets in their free ends, curved springs resting with their center part on the center part of the upper press plate, and eccentric levers in the eyelets and adapted to depress the ends of the springs.

In testimony whereof I have hereunto signed my name this 20 day of March 1908, in the presence of two subscribing witnesses.

KARL LENCK.
